By Inventor

Robert S. Randle

Attorney.

UNITED STATES PATENT OFFICE.

BERNARD A. KENNEPOHL, OF RICHMOND, INDIANA.

WATER-HEATER.

No. 890,237.

Specification of Letters Patent.

Patented June 9, 1908.

Application filed August 21, 1907. Serial No. 389,423.

To all whom it may concern:

Be it known that I, BERNARD A. KENNEPOHL, a citizen of the United States, residing in Richmond, in the county of Wayne and 5 State of Indiana, have invented certain new and useful Improvements in Water-Heaters, of which the following is a full and accurate specification and exposition, being such as will enable others to make and use the same 10 with absolute exactitude.

The object of my invention, broadly speaking, is to provide a water-heater which will be strong and durable in construction; being so formed as to occupy a minimum amount of 15 space; which will be inexpensive to install and maintain; by which water may be easily and quickly heated to the temperature desired with a minimum amount of fuel; and to provide a heater which can be sold at a comparatively low price.

More specifically stated, my object is to provide a quick water-heater of simple and inexpensive construction and which will be efficient in operation.

Other objects and particular advantages 25 of my invention will be brought out in the course of the specification, and the features which are new and useful will be accentuated in the appended claim.

One manner for carrying out the principles 30 of my invention, and that which in practice has been found to be the most desirable, is shown most clearly in the accompanying drawings, in which—

Figure 1 is a side elevation of my invention complete and in operative position, portions 35 being shown as broken away in order to more clearly show the interior construction of the invention. Fig. 2 is a plan view of the upper end of the heater. Fig. 3 is a plan view of the upper end of the heater with the heat dome removed. Fig. 4 is a central cross sectional view of the heater. And Fig. 5 is a plan view of the lower end of the heater.

Similar indices denote like parts throughout the several views of the drawings.

In order that the construction and operation of my invention may be more clearly understood and its advantages be fully appreciated I will now take up a detail exposition thereof in which I will describe the several parts as briefly and as compactly as I may.

In this instance the letter A designates the 55 body of the heater, which in fact is a cylind-

rical oblong casing adapted to stand in a vertical position as shown. The upper end of the body is closed by the top B, and the lower end is closed by the concavo-convex bottom C. The bottom is formed to curve upwards within the body to form a comparatively large combustion chamber D, as shown in Fig. 1.

The numerals 1, 2 and 3 denote flues which connect the top B and the bottom C and open therethrough.

The letter E denotes the heat dome, which is permanently secured, as by tap bolts, to and rises above the top B forming a heat chamber into which opens the upper end of 70 the flues. In the top of said dome is an aperture adapted to be opened or closed by the damper F, which damper is adapted to be turned being mounted on the pivot G. A second aperture is formed through the heat- 75 dome in which aperture is threaded the escape pipe H. Said pipe H is provided with a valve I from which a pipe J may be extended to any point desired, as to the outside of the building.

The heater is carried by a pedestal K, to the upwardly extending arms of which it is secured, and by which the heater is supported at the desired distance from the floor as shown.

The numeral 4 denotes the outlet pipe extending through the top B and by means of which water may be withdrawn from the interior of the heater and controlled by the faucet 5, which latter may be located at any 90 convenient point desired.

The numeral 6 denotes an inlet pipe, controlled by the valve 7, through which water may be injected into the boiler.

The numeral 8 denotes a gas burner located centrally in the combustion chamber D, being connected to the mixer 9, with a pipe 10 leading out therefrom to the fuel supply, and controlled by the valve 11.

The numeral 12 designates a faucet 100 through which water may be withdrawn from the heater, and by which the heater may be drained.

Operation: From the above the reader will have opined that the heater is to be supplied with water; gas is then allowed to flow through the pipe 10, then lighted, and radiate as a flame from the burner 8 throughout the combustion chamber D. It is quite evident that the heat will pass up through the flues 110

1, 2 and 3, and if the damper F be open then the surplus heat will pass out into the room through the aperture which the damper controls, or if preferred said aperture may be 5 closed by the damper and the valve I may be opened, thereby allowing the surplus heat from the burning gas to be conducted outside the building in which the heater is located. The particular feature of this invention, however, is that I provide a comparatively large heating surface, comprising the combustion chamber below, the heat-dome above, and a plurality of flues passing through the heater longitudinally and connecting said 10 combustion-chamber and heat-dome. In operation, after the heater has warmed up, and the flame from the burner is in good trim, then the escape of the heat from the dome may be retarded or entirely shut off, particularly if the blaze be turned low, thereby utilizing practically all of the heat from the fuel.

From the foregoing, it will be understood that under certain conditions both the damper F and valve I may be open. Such 25 would be the arrangement, for instance, in order to secure the maximum amount of draft through the flues, with a resultant correspondingly rapid heating of the water. When, however, it would be desired to reduce the expenditure of heat, or to vary the 30 discharge of the products of combustion, either or both of said valves would be either wholly or partially closed, as desired. After the water is once heated, and unless a large 35 quantity of cold water is admitted to the boiler on account of the use of the heated water, the amount of gas or fuel required to maintain the water in the boiler at a proper temperature would be as a matter of course 40 reduced, and when less heat is employed it

may be required or desirable to modify the position of the valves accordingly.

I reserve the privilege of making changes in the details of construction without departing from the spirit of my invention or sacrificing any of the advantages thereof. 45

Having now fully shown and described my invention and the best means for its construction and operation to me known at this time, what I claim and desire to secure by 50 Letters Patent of the United States, is—

A water heater comprising an elongated water-tank which is round in cross section having means whereby water may be injected thereinto and means whereby the 55 water may be withdrawn therefrom, a concavo-convex permanent bottom for the tank located above the lower end thereof forming a combustion chamber, a permanent top for the tank, a heat-dome secured on the top, a 60 plurality of permanent plain heat-flues extending longitudinally through the tank and connecting the top and the bottom and connecting the interior of the combustion chamber with the interior of the heat-dome, a 65 single gas-burner located in the combustion chamber, and means for ventilating the heat-dome, said ventilating means including a damper movable in a horizontal plane on a vertical pivot and a valved flue connected 70 with said dome, all substantially as shown and described and for the purposes set forth.

In testimony whereof I have hereunto subscribed my name to this specification in the presence of two subscribing witnesses.

BERNARD A. KENNEPOHL.
